ABSTRACT OF THE DISCLOSURE

In an electron gun for generating and focusing an electron beam having at least a cathode and at least first, second, third and fourth electrodes successively axially arranged in the advance direction of the electron beam emitted from the cathode, the second electrode has an aperture therein with a diameter at least twice the diameter of an aperture in the first electrode, and the second electrode is maintained at ground potential and the fourth electrode is maintained substantially at ground potential.

This invention relates generally to improvements in electron guns of the type employed in the reception of television signals, and more particularly to a cathode ray tube particularly suited for use in chromatron type television receivers.

In conventional cathode ray tubes the lens system generally consists of four grid electrodes. The diameter of the aperture in the second grid is substantially the same as the diameter of the aperture in the first grid in order to prevent the cathode from being subjected to variations in the anode voltage. In this type of configuration the cathode is shielded by the second grid from variations in the anode voltage or from the high voltage present on the third grid. In addition, since the path of the electron beam is encircled by the tubular portion of the second grid the electron beam path is shielded from asymmetrical fields which are produced by the supporting pins on the electrodes. The disadvantages with this type of configuration, however, are that the modulation characteristic is poor and the assembling process is tedious and inefficient due to the necessity of aligning the apertures in the grids.

In another type of prior art cathode ray tube the second or accelerating grid is eliminated which avoids the disadvantages set forth above. In this type of arrangement, however, there are other disadvantages which render this type of construction unsuitable for a chromatron type of cathode ray tube.

In view of the foregoing it is the primary object of the present invention to provide an electron gun which has the advantages but not the disadvantages of prior art electron guns.

Another object of the present invention is to provide a cathode ray tube which eliminates any momentary discharge between adjacent electrodes, particularly between the anode and the first grid of the electron gun. In this manner, breakdown of electrical parts associated with the cathode ray tube such as transistors, diodes and other semi-conductor devices is avoided.

These and further objects, features and advantages of the present invention will appear from the following detailed description of one embodiment of the invention which is to be read in conjunction with the accompanying drawings wherein like components in the several views are identified by the same reference numeral.

In the drawings:

FIGURE 1 is a schematic diagram of a conventional electron gun having a lens system consisting of four grid

FIGURE 8 is a graph illustrating the relationship of the aperture diameter of the second grid to the distance between the first and second grids in the device of the present invention, the cut-off voltage being a parameter;

FIGURE 9 is a graph showing the relationship between the distance between the first and second grids and the lens effect in the device of the present invention, the aperture diameter of the second grid being the parameter;

FIGURE 10 is a diagram schematically illustrating the field distribution of the device of the present invention; and

FIGURE 11 schematically illustrates another embodiment of this invention.

In order to facilitate a better understanding of the present invention, a description will first be given of a conventional electron gun such, for example, as an unipotential focus-type electron gun having a lens system consisting of four and three grid electrodes respectively, indicated generally as DA and DB in FIGURES 1 and 2. As illustrated in FIGURE 1, the electron gun DA comprises cup-shaped first, second, third, fourth and fifth grids designated as G_{A1}, G_{A2}, G_{A3}, G_{A4} and G_{A5}. These grids are sequentially arranged in the direction X of travel of an electron beam emitted from a cathode K_A, the first grid G_{A1} constituting a first lens, the third grid G_{A3} being of an unipotential electrode structure and constituting a second lens or the main lens, and the fifth grid G_{A5} being held at the same potential as the third grid G_{A3} and supplied with a high voltage. In this case, the diameter of an aperture h_{A2} of the second grid G_{A2} is selected to be substantially the same as that of the aperture h_{A1} in the first grid G_{A1}.

The electron gun DB (FIGURE 2) is of the type in which the second or accelerating grid G_{A2} of the electron gun DA illustrated in FIGURE 1 has been eliminated. With this exception, the electron gun DB is exactly the same in structure as the electron gun DA. That is, the electron gun DB comprises a cathode K_B, first, second, third and fourth grids G_{B1}, G_{B2}, G_{B3}, G_{B4} which are sequentially arranged in the same manner as in FIGURE 1.

These electron guns DA and DB will now be compared from the viewpoint of their advantages and disadvantages.

In the electron gun DA which has a lens system consisting of four grid electrodes and which is illustrated in FIGURE 1, the diameter of the aperture h_{A2} of the second grid G_{A2} is substantially the same as that of the aperture h_{A1} of the first grid G_{A1}. In this manner the cathode K_A is shielded by the grid G_{A2} from the influence of the anode voltage or a high voltage present on the third grid

G_{A3} . In other words, the cathode K_A is not subjected to variations in the anode voltage. Further, since the path of the electron beam is encircled by the tubular portion of the second grid G_{A2} , the electron beam path can be shielded from asymmetrical fields produced by the supporting pins of the respective electrodes. On the other hand, however, the second grid G_{A2} is placed relatively close to the first grid G_{A1} and the diameter of its aperture h_{A2} is small, with the result that the modulation characteristic is poor. In addition to this, since the diameter of the apertures h_{A1} and h_{A2} of the first and the second grids G_{A1} and G_{A2} are selected as small as 0.6 mm or so, the centering of the apertures h_{A1} and h_{A2} requires great precision, which causes remarkably reduced efficiency in the assembling process.

The other prior art electron gun DB illustrated in FIGURE 2 is not provided with an accelerating electrode such as that corresponding to the second grid G_{A2} of the electron gun DA. Accordingly the electron gun DB does not have the disadvantages enumerated above for the electron gun DA. That is, the centering of the grid electrodes does not require great precision such as in the electron gun DA, so that assembly is relatively easy and the modulations characteristic gm is excellent. On the other hand, however, the electron gun DB does not possess the advantages which emanate from the provision of the second grid G_{A2} in the electron gun DA, and accordingly this type of electron gun is not suitable for use in the Chromatron-type cathode ray tube.

The present invention will not be described in detail with reference to FIGURES 3 to 10 inclusive. In FIGURE 3 the reference character T designates in general a device produced in accordance with the present invention. As illustrated in the figure, there is provided in the neck portion 41a of the cathode ray tube 41 an electron gun D comprising first, second, third, fourth and fifth grids G_1 , G_2 , G_3 , G_4 and G_5 sequentially arranged in the direction X of travel of an electron beam emitted from a cathode K. The third grid G_3 is an anode which constitutes a unipotential-type focus lens and is supplied with a high voltage, the fourth grid G_4 is the so-called focus electrode and the fifth grid G_5 is an anode which is supplied with the same high voltage as that applied to the third grid G_3 .

The interior of the funnel portion 41b of the cathode ray tube 41 is coated with an inner conductive film 42 such as in conventional cathode ray tubes, and high voltage of from 10 to 25 kv. is applied from a power source E to the inner conductive film 42 and the third and fifth grid electrodes G_3 and G_5 of the electron gun D through an anode terminal 43 or the so-called anode button provided on the funnel portion 41b. The outer circumferential surface of the funnel portion 41b of the cathode ray tube 41 is coated with an outer conductive film 44 and the conductive film 44 is grounded to, for example, the chassis of the cathode ray tube 41.

In the device of the present invention both or either one of the second and fourth grids G_2 and G_4 of the electron gun D is connected to, for example, the outer conductive film 44 of the cathode ray tube 41, so as to be operated at chassis potential or ground potential which might be said to be the common potential of the cathode ray tube.

As illustrated in FIGURE 4, the first grid G_1 of the electron gun D can be formed cup-shaped which comprises a tubular portion 1a and a closed end face 1b having bored therein an aperture h_1 . The aperture h_1 has a diameter d_1 which is a minimum value for the production of a necessary beam current. It is usually selected in the range of from 0.3 to 1.5 mm., and preferably is 0.9 mm.

The second grid G_2 can also be formed cup-shaped and comprises a tubular portion 2a having a diameter substantially equal to that of the tubular 1a of the first

grid G_1 and a closed end face 2b. The second grid G_2 has formed in the closed end face 2b thereof an aperture h_2 which is substantially coaxial with the aperture h_1 of the first grid G_1 in opposing relation thereto. In this case, the diameter d_2 of the aperture h_2 is selected to be more than two times the diameter d_1 for example, with the relationship $d_2=4d_1$. The second grid G_2 is not always required to be cup-shaped and the closed end face 2b may if desired be eliminated.

The distance S_{12} between the first and second grids G_1 and G_2 is selected to be in the range of from 0.08 to 0.5 mm., for example, 0.335 mm. Each of the third, fourth and fifth grids G_3 , G_4 and G_5 constituting a unipotential focus lens can be formed in such a shape as to correspond to each grid electrode of a conventional unipotential-type electron gun. In accordance with the present invention, the diameters d_3 and d_3' of apertures h_3 and h_3' of the third grid G_3 are selected to be about two times the diameter d_1 of the aperture h_1 of the first grid G_1 and the diameter d_5 of an aperture h_5 of the fifth grid G_5 is selected to be about three times the diameter d_1 of the aperture h_1 of the first grid G_1 . An anode voltage of, for example, about 18 kv. is applied to the third and fifth grids G_3 and G_5 .

In order to ground the fourth grid G_4 , the third and fifth grids G_3 and G_5 are spaced apart a distance such that the unipotential-type main lens system constituted by the third, fourth and fifth grids G_3 , G_4 and G_5 is in an optimum focusing condition when the fourth grid 30 G_4 is at the ground potential. That is, the focal length of the main lens formed by the third, fourth and fifth grids G_3 , G_4 and G_5 decreases with an increase in the distance between the third and fifth grids G_3 and G_5 and the focal length also decreases with a decrease in the 35 potential difference between the fourth grid G_4 and the third and fifth grids G_3 and G_5 . Therefore, the distance S_{35} between the third and fifth grids G_3 and G_5 is selected in such a manner that a predetermined main lens is constituted when the fourth G_4 is at the ground potential. 40 Heretofore, the fourth grid G_4 has usually been operated at a higher potential than the ground potential. In this invention the fourth grid G_4 is held at approximately the ground potential and the distance S_{35} between the third and fifth grids G_3 and G_5 is selected to be longer than that in the prior art, for example, 11 mm. in order that the potential difference between the fourth grid G_4 and the third and fifth grids G_3 and G_5 may be great.

The reason why the second grid G_2 is held at ground potential can be seen by ascertaining the relationship between the potential E_{c2} of the second grid G_2 and the cut-off voltage. In FIGURE 7 curves 31, 32, 33 and 34 respectively illustrate the relationship between the second grid voltage E_{c2} and the cut-off voltage E_{c0} obtained when the anode voltage E_b was selected to be 10 kv., 15 kv., 16 kv. and 18 kv. respectively in the embodiment above described (FIGURE 4). As is apparent from the graph of FIGURE 7 the cut-off voltage is not substantially dependent upon the voltage of the second 50 grid G_2 , and hence even if the second grid G_2 is held at ground potential, the cut-off voltage is not appreciably affected. According to this invention, the electron gun D is provided with a second grid G_2 and its tubular portion 2a serves to shield the electron beam path from the 55 asymmetrical fields as mentioned previously.

In the graphs of FIGURES 5 and 6 the full-line curve 11 represents the relationship between the cut-off voltage E_{c0} in the electron gun of the aforementioned structure (FIGURE 4) and the voltage E_b applied to the third and fifth grids G_3 and G_5 while the other full-line curve 12 indicates the relationship between the cut-off voltage 70 and the voltage E_{c2} of the second grid G_2 . In FIGURE 5 the broken line curve 13 indicates the relationship between the impressed voltage on the third and fifth grids 75

G_{A3} and G_{A5} and the cut-off voltage E_{c0} in the electron gun DA, while the other broken line curve 14 represents the relationship between the impressed voltage on the second and fourth grids G_{B2} and G_{B4} and the cut-off voltage E_{c0} in the electron gun DB. In FIGURE 6 the dotted-line curve 15 is a characteristic curve of the impressed voltage on the second grid G_{A2} with respect to the cut-off voltage E_{c0} in the electron gun DA.

As is apparent from these curves, and particularly curve 12, in the present invention the cut-off voltage E_{c0} is practically independent of variations in the second grid voltage E_{c2} . That is, the cut-off characteristics are not affected by the second grid G_2 . Further, the plot of cut-off voltage E_{c0} vs. anode voltage E_b for the device of the present invention (curve 11) is similar to that for the electron gun DB (curve 14) having a lens consisting of three grid electrodes. Accordingly, the modulation characteristic gm of the electron gun D of the present invention is improved to the same extent as that for the electron gun DB.

In the electron gun D produced in accordance with the present invention the diameter d_2 of the departure h_2 of the second grid G_2 is selected to be greater than one and one half times the diameter d_1 of the aperture h_1 of the first grid G_1 , so that the precision required in the centering of the apertures h_1 and h_2 is not as great as in the prior art electron gun DA. This facilitates the assembling of the electron gun device of this invention.

As has been described in the foregoing, the electron gun D has almost all the merits of conventional electron guns but in the electron gun D the cathode K is not protected from the anode voltage, since the diameter d_2 of the aperture h_2 of the second grid G_2 is selected to be about two times the diameter d_1 of the aperture h_1 of the first grid G_1 . As indicated in FIGURE 5 by the curve 11, the cut-off voltage E_{c0} varies in proportion to the anode voltage E_b . The variations of the anode voltage, however, can be suppressed satisfactorily by various circuit arrangements, so that it does not offset the operation of the device of the present invention.

In the electron gun D the diameter d_2 of the aperture h_2 of the second grid G_2 is large and a high voltage of 15 to 20 kv. is applied to the third grid G_3 , so that the distance S_{12} between the first and second grids G_1 and G_2 can be selected to be long. In addition to this, since the diameter, 45 d_2 of the aperture h_2 of the second grid G_2 is large, the opposing areas between the first and second grids G_1 and G_2 is small. As a result, the electrostatic capacity produced between the first and second grids can be decreased, which effectively prevents a discharge current from flowing in a 50 pulsating manner from the second grid G_2 to the first grid G_1 and the cathode K, as compared with the prior art electron gun DA having a lens consisting of four grid electrodes.

In prior art electron guns having a lens consisting of 55 three grid electrodes, it is difficult to effect prefocusing and an electric field formed between the first grid G_1 and the anode performs a concave lens effect, so that the structure of the prior art electron guns of this type have the disadvantage of spherical aberration. In the present invention, however, a weak convex lens is produced by suitably selecting the diameter d_2 of the aperture h_2 of the second grid G_2 and the distance S_{12} between the first and second grids G_1 and G_2 , by which prefocusing can be effected.

In FIGURE 8 curves 16, 17, 18 and 19 respectively indicate the relationship between the diameter d_2 of the aperture h_2 of the second grid G_2 and the distance between the first and second grids G_1 and G_2 in the cases where the cut-off voltage is -80 v., -90 v., -100 v. and -120 v. when the diameter d_1 of the aperture h_1 of the first grid G_1 is constant. In FIGURE 9 curves 20, 21 and 22 respectively represent the relationship between the distance S_{12} between the first and second grids G_1 and G_2

and the lens effect when the diameter d_1 of the aperture h_1 of the first grid G_1 is constant but the diameter d_2 of the aperture h_2 of the second grid G_2 is a variable, the abscissa representing the distance S_{12} between the first and second grids G_1 and G_2 and the ordinate representing the lens effect. In this graph the convex lens effect is shown above the zero point and the concave lens effect is shown under the zero point. In this case the inflection points of the curves shift to the right when the depth of the cup-shaped grid G_2 and the projection of the grid G_3 are small, and the inflection points move to the left when the depth of the grid G_2 and the projection of the grid G_3 are great.

As can be seen from the curves in FIGURES 8 and 9, 15 with suitable selection of the cut-off voltage, the diameter d_2 of the aperture h_2 of the second grid G_2 and the distance S_{12} between the first and second grids G_1 and G_2 , a pre-focusing lens having a convex lens effect can be produced by the first and second grids G_1 and G_2 . That is, in a system having a cathode K, a first grid G_1 , a second grid G_2 and a third grid G_3 , an electric field distribution can be produced which forms a pre-focusing lens L_1 having a convex lens effect, as illustrated in FIGURE 10. In this case a concave lens L_2 is formed in the vicinity 20 of the aperture h_3 of the third grid G_3 , but it is sufficient that the composite lens formed by the lenses L_1 and L_2 has only a convex lens effect. In this figure reference character P indicates a crossover point.

According to this invention the second grid G_2 and/or 30 the fourth grid G_4 are grounded, and hence the second grid G_2 and/or the fourth grid G_4 serves as a lightning-conductor. As a result of this, it is possible to prevent discharges which might otherwise be caused between the third and fifth grids G_3 and G_5 when these grids are supplied with a high voltage as well as another electrode, for example, the first grid G_1 . At the same time, when discharge is actually caused between the third and fifth grids G_3 and G_5 and the second grid G_2 and/or the fourth grid G_4 , this discharge current can be prevented from 35 flowing to circuit elements, thereby avoiding breakdown thereof.

One embodiment of this invention as applied to a 12 inch gun is as follows:

$$d_1 = 0.6\phi$$

$$d_2 = 4\phi$$

$$d_3 = 2\phi$$

$$d_3' = 2\phi$$

$$d_5 = 3\phi$$

$$S_{12} = 0.335 \text{ mm.}$$

$$S_{35} = 11 \text{ mm.}$$

$$\frac{d_2}{d_1} = 6.7$$

While the present invention has been described in connection with a unipotential-type electron gun it is to be understood that in a tripotential-type one such as shown in FIGURE 11 a similar effect of discharge prevention can be obtained where the diameter of the second grid G_2 is selected to be two times that of the first grid G_1 and then grounded.

It will be apparent to those skilled in the art that many modifications and variations may be effected without departing from the scope of the novel concepts of this invention.

What is claimed is:

1. An electron gun for generating and focusing an electron beam, said gun comprising a cathode, first, second, third and fourth control electrodes and an anode, said control electrodes and anode being axially arranged in the advance direction of said electron beam, said electrodes having axial apertures therein, the aperture in said second electrodes having a diameter at least twice as large as the diameter of the aperture of said first electrode, means maintaining said second electrode at ground poten-

tial, and means maintaining said fourth electrode substantially at ground potential.

2. A lens system for use in an electron gun for focusing an electron beam emitted from a cathode, said lens system comprising first, second, third, fourth and fifth electrodes, said electrodes being axially arranged in the advance direction of said electron beam, said electrodes having axial apertures therein, the aperture in said second electrode having a diameter at least twice as large as the diameter of the aperture of said first electrode, means maintaining said second electrode at ground potential, and means maintaining said fourth electrode substantially at said ground potential.

3. A device in accordance with claim 2 wherein said second and fourth control electrodes are interconnected.

4. A device in accordance with claim 3 wherein said third and fifth electrodes are interconnected and have applied thereto a high voltage.

5. A device in accordance with claim 4 wherein the spacing between the first and second electrodes is approximately 0.08 to 0.5 mm.

5
